CLAIM

The ornamental design for a front fender for a vehicle as shown and described.

DESCRIPTION

This application contains subject matter related to the following co-pending U.S. design patent applications: application Ser. No. 29/851,216, filed Aug. 26, 2022 and entitled “Front Fender for a Vehicle”; application Ser. No. 29/919,503, filed herewith and entitled “Motor Vehicle, Toy Replica, and/or Other Replica”; application Ser. No. 29/919,505, filed herewith and entitled “Motor Vehicle, Toy Replica, and/or Other Replica”; and application Ser. No. 29/919,507, filed herewith and entitled “Motor Vehicle, Toy Replica, and/or Other Replica”.

FIG. 1 is a front view of a front fender for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
